METHOD OF MAKING FRAGMENTATION BOMBS

John C. Whitesell, Jr., Philadelphia, Pa., assignor to Edward G. Budd Manufacturing Company, Philadelphia, Pa., a corporation of Pennsylvania

Original application September 4, 1943, Serial No. 501,202. Divided and this application September 27, 1944, Serial No. 556,068

1 Claim. (Cl. 29—1.21)

This application is a division of my copending application Serial No. 501,202, filed September 4, 1943.

This invention relates to that class of munitions known as fragmentation bombs, and particularly to improvements in the construction thereof and in the method of manufacturing the same.

One form of conventional fragmentation bomb embodies a cylindrical tube surrounded by a spirally wound wire fragmentation element and having at its nose and tail ends cup-shaped castings threaded thereto. The function of these castings is, in addition to supporting the stabilizing element and the detonators, to provide a means for holding the spiral fragmentation element in place. Such castings, however, do not contribute to the bomb's fragmentation, but, as a matter of fact, since they overlap the ends of the cylindrical tube, tend to reduce the amount of possible maximum fragmentation.

The present invention has for its objects a new method of providing features of construction in a fragmentation bomb which will increase fragmentation to a veritable maximum, and an improved and economical method of construction and assembly by means of which fragmentation bombs can be rapidly and easily produced in quantity production.

With the above and other objects in view which will be apparent from the following detailed drawing, to those skilled in the art, the present invention consists in certain features of construction and combinations of parts to be hereinafter described with reference to the accompanying drawing, and then claimed.

In the drawing which illustrates a suitable embodiment of the invention,

Figure 1 is a view of the fragmentation bomb, partially in section to better illustrate the construction thereof;

Figure 2 is a transverse section taken substantially on line 2—2 of Figure 1; and

Figure 3 is a view somewhat similar to Figure 1, but showing the bomb in the process of assembly.

Referring to the drawing in which like numerals refer to like parts throughout the views, the fragmentation bomb constructed in accordance with the present invention embodies a tubular metal member 10 whose interior wall forms the explosive chamber, a nose end element 11 for supporting a detonating device (not shown), a tail end element 12 for supporting a finned stabilizing element (not shown), the spirally 55

wound wire fragmentation element 13, and a stream-lining cup 14 for the leading end of the bomb casing.

It is to be noted that the spring or fragmentation element 13, the individual coils of which may be of square or other suitable shape in cross-section, extends for the full length of the tubular metal member 10. By so extending the fragmentation element 13 for the full tube length, the amount of fragmentation is increased to a maximum since it is coextensive with the explosive charge to be contained within the tube 10.

The various elements described as constituting the bomb casing are so constructed as to facilitate production in large quantities by simple operations.

The metal tubular member after being cut to length is swaged down on both ends to a diameter to snugly receive the nose and tail and elements or adaptors 11 and 12, respectively. The nose end adaptor 11 is in the form of an internally threaded sleeve and the tail end adaptor 12 is in the form of an externally threaded shouldered plug. These elements are such that they 20 can be produced as screw machine products. The elements 11 and 12 snugly fit within the swaged-down ends of the tube 10 and are secured in place by arc welding, as indicated by the weld metal at 15 and 16, respectively, the welding being such 25 as to provide an integral gas-tight connection between elements 11 and 12 and the tube.

The spring or fragmentation element 13, the individual turns thereof firmly abutting each other, is formed on suitable coiling equipment in 30 two sections 13a and 13b, each tapering in diameter at one end according to the contour of the adjacent tube end. The coil sections 13a and 13b, as shown in Figure 3, are slipped on the tubular member 10 from its opposite ends into 35 abutting relation. In this position the endmost turns of the coil abut the walls of the adjacent ends of the tube, the endmost turn of the section 13a closely surrounding the nose end adaptor 11. The two coil sections are then arc welded 40 together at the adjacent wire ends as indicated at 17 in Figures 1 and 2, the excess weld material being ground or filed off to present a smooth surface continuous with the coil surface. During the assembly of the coil sections 13a and 13b, 45 the free ends may be tacked by arc welding to the tube 10 to prevent unwinding or pulling away from the ends of the tube. In the case of the trailing section 13b, the end turn may be welded directly to the tube 10 as indicated at 18 in Figure 1, and the endmost turn of the leading sec-

tion 13a may be welded to the adaptor 11 as indicated at 19 in Figure 1. This tack welding may be done while the spring is under compression so that in the final assembly the spring or fragmentation element will firmly hug the tube 10 at all points.

In order to better the aerodynamic effect at the nose end of the bomb casing, the streamlining cup 14 is fitted over the leading end of coil section 13a and may be tack welded in place as indicated by the weld metal 20, or otherwise secured in place, as desired.

Suitable handling loops 21 may be secured to the fragmentation element 13 as desired.

The principal advantage of the fragmentation bomb of the present invention is that by increasing the length of spring wire which constitutes the fragmentation element, a more effective bomb is produced with the same tube length and explosive charge as is employed in a conventional structure.

A further advantage resides in the fact that by reducing the machine work, through the elimination of the conventional end castings, the unit cost of production is reduced.

It is to be understood that various changes may be made in the detailed procedure described without departing from the spirit and substance of the present invention, the scope of which is defined by the appended claim.

What is claimed is:

In the manufacture of a fragmentation bomb, the steps of gradually decreasing the diameter of the ends of a tubular member to predetermined surface contour and length, spirally winding a pair of wire elements to an internal diameter of substantially that of the diameter of the casing with the turns of each in engagement with each other and with the turns at one end of each decreasing in diameter to the same degree as an end of the tubular member, telescoping the spirally wound elements over the tubular member from the opposite ends thereof to axially engage the ends thereof with the decreased-diameter ends of the tubular member and to register the end of the wire of one wire element with the corresponding end of the other wire element, and then rigidly securing said registered ends of the wire elements together.
